CLAIM

The ornamental design for a rear stand for a spoiler, as shown and described.

DESCRIPTION

FIG. 1 is a front right perspective view of a rear stand for a spoiler according to the present invention.

FIG. 2 is a front left perspective view of the rear stand for a spoiler shown in FIG. 1.

FIG. 3 is a rear right perspective view thereof.

FIG. 4 is a front left bottom perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof; and,

FIG. 10 is a bottom view thereof.

The superimposed areas encased in broken lines, shown in the drawings, illustrate portions of the rear stand for a spoiler and form no part of the claimed design.
